STARTING AND OPERATING CIRCUIT FOR FLUORESCENT LAMP

William S. H. Hamilton, Larchmont, N. Y.

Application February 15, 1950, Serial No. 144,345

3 Claims. (Cl. 315—103)

This invention relates to improvements in starting and operating circuits for fluorescent lamps, particularly those operated on 60-volt and 110-volt D. C. and A. C. sources of current supply, such as lamps of the 12", T-8 (1 dia.), 15", T-12 (1½ dia.), 18", T-12 (1½ dia.) and 24", T-12 (1½ dia.) types, but which are adapted for use in connection with other hot-cathode lamps having like operating characteristics.

One object of the invention is to provide novel and improved circuit organizations employing a thermo-electro-magnetic starter, preferably but not necessarily of plug-in type, for supplying preheating and operating current to the lamp in such a manner as to secure quick starting and re-starting actions.

Another object of the invention is to provide a starter embodying a thermal switch and a relay operating in conjunction therewith to preheat the lamp and to stop the preheating action and start the lamp into operation as soon as it is sufficiently heated to fire.

Still another object of the invention is to provide a starter of the described type which will permit of a practically instantaneous restarting of a lamp which has been turned off and then turned on again shortly, regardless of the position of the thermal switch.

Still another object of the invention is to provide a starter of the type described in which a thermal switch and a relay are so compactly constructed, combined and arranged for use as to adapt the same to be enclosed in a plug-in "can" or casing of the same or practically the same size as that of a conventional starter, such as the FS-44 starter, and used in the same or a similar socket with little or no circuit wiring changes.

Still another object of the invention is to provide a starter of this type which is simple of construction, reliable and efficient in operation, and adapted as exemplificatively disclosed or in suitably modified forms to be used in connection with different types of lamps operating on either D. C. or A. C. sources of current supply.

With these and other objects in view, which will appear in the course of the subjoined description, the invention consists of the novel features of construction, combination and arrangements of parts hereinafter more fully set forth, and as shown in the accompanying drawings, in which:

Figure 1 is a schematic diagram of one form of circuit as adapted for operation with a D. C. fluorescent lamp and employing a thermo-electro-magnetic starter embodying my invention, showing the parts in normal starting position.

Fig. 2 shows an enlarged detail view of the circuit disclosed in Fig. 1, showing the starter switches as normally arranged in closed position for a starting action.

Fig. 3 is a similar view showing the relay switch opened to break the preheating circuit and showing in full and dotted lines closed and opened positions of the thermo-static switch. This figure shows in full lines the arrangement of the parts after the lamp has been operating for a few seconds.

2

Fig. 4 is a modified form of the circuit shown in Fig. 1 and using the same type of starter.

Fig. 5 is a diagram of a still further modified form of circuit employing a modified form of starter, the parts appearing in normal position ready to start the lamp.

Fig. 6 is an enlarged detail view of a portion of the circuit shown in Fig. 5 showing the starter in the position taken after the lamp has been operating for a few seconds.

Fig. 7 is a diagram of a still further modified form of circuit employing a starter of the type shown in Figs. 5 and 6, the parts appearing in normal position ready to start the lamp.

Fig. 8 is an enlarged detail view of a portion of the circuit shown in Fig. 7 with the starter in the position taken after the lamp has been operating for a few seconds.

Fig. 9 is a view in front elevation of my invention as embodied in a starter adapted for use in connection with a lamp socket, showing the starter casing body in vertical section.

Fig. 10 is a similar view in rear elevation of the starter.

Fig. 11 is a section through the starter on an enlarged scale taken on line 11—11 of Fig. 9.

Figs. 12 and 13 are horizontal transverse sections taken on lines 12—12 and 13—13 of Fig. 9.

Fig. 14 is a view of the thermostatic switch supporting disk and the switch heater carried thereby.

Referring now particularly to Fig. 1 of the drawings, 1 represents the gas containing envelope of the lamp having the negative cathode and positive filamentary electrodes 2 and 3, respectively, at least one of which is adapted to be preheated to start the lamp. In the case of a circuit such as shown in Fig. 1, which is designed to operate primarily on D. C., it is only necessary to heat the negative cathode filament, so that the positive filament may be short circuited. Connected with these electrodes are operating conductors or leads 4 and 5 forming with the electrodes an operating circuit, which conductors are adapted to be connected at points 6 and 7 to the terminals of a line, or supply, circuit adapted to be opened and closed in practice by suitable means. In the input and output portions of conductor 4 are arranged an inductive reactance 8 and a ballast lamp 9, which may be of any suitable type, and included also in this conductor is the coil, or winding, 10 of the relay of the combined thermal and relay switch device, hereinafter described.

Extending from the conductor 4 at a point between the reactance 8 and the lamp is a preheating conductor comprising input and output branches, or sections, 11 and 12 and an intermediate switch circuit branch 13. A relay, or electro-magnetic, switch 14 normally connects through its contacts 15, 15' and the output end of branch 11 with the input end of branch 13 and a thermostatic, or thermally operated, switch 16 normally connects through its contacts 17, 17' the output end of branch 13 with the input end of branch 12. In the branch 12 is a current limiting resistance 18 and in the branch 13 is a heating resistance 19 for heating the switch 16. An arc suppressing condenser 20 extends across the adjacent ends of branches 11 and 12 to suppress or reduce the arcing at the contacts of the thermal switch or relay when breaking the circuit through the reactance 8.

The conductors 11, 12, 13, and switches 14 and 16 form the component parts of a preheating circuit of the starter which governs the flow of preheating current to the lamp. Normally the switches are closed as shown to coactively establish a preheating circuit to preheat the filament when the line circuit is closed for a starting action, which preheating circuit is automatically broken by contacts 17, 17' of thermal switch 16 when the filament 2 is sufficiently heated and the lamp passes current to fire the lamp and energize the coil 10 of the relay and establish the operating circuit connections. In practice the

switch elements and their coating members are preferably arranged as an assembly so aligned that they may be disposed in close compass and so as to be enclosed within a "can" or plug-in container casing having plug-in prongs or contacts to fit within a receiving socket for connection with the associated conductors.

The arrangement of the parts comprising the starter may, in fact, be such as to adapt them to fit within a can of the same size as the can of the well known FS-44 starter. By this means a combined thermal switch and relay starter embodying my invention may be used in connection with installed lamps of the types described and other similar types with little or no rewiring. A further advantage of this structure is that, if mounted in an FS-44 starter socket, it will be reversible as to position, as said socket is so arranged by the size of its openings to receive the prongs of the starter in only two positions, either of which gives proper operation of the circuit.

The relay may be of any suitable type and for simplicity may be of the type shown in Figs. 2 and 3 in which the switch 14 is spring closed automatically and adapted to be opened when attracted by energization of coil 10, while thermostatic switch 16 may be one of quick-acting snap type comprising a switch member 16 connected by an insulated stem to a concavo-convex thermostatic disk 16' normally bowed in one direction to hold switch 16 closed and adapted to be bowed in the opposite direction when heated by the resistance 19 to open the switch. I, however, do not limit myself to the use of these particular types of relays and switches, as others suitable for the purpose may be employed.

In the operation of the lamp circuit shown in Fig. 1 when current is applied to the line it flows through the reactance 8, through the contacts 15, 15' of the relay switch 14, through the heating coil 19 of the thermostatic switch 16, and through the contacts 17, 17' of this switch and resistance 18 and the cathode filament 2 of the lamp, thus establishing a preheating circuit to preheat the filament 2. At the same time an operating circuit is also established from the low side of the reactance 8, through the coil 10 of the relay, through the ballast lamp 9 and into the positive filament 3 to apply less than line voltage to the lamp so that if, before the thermal switch 16 opens its contacts 17, 17' enough current is passed by the lamp to sufficiently energize the relay coil 10, the contacts 15, 15' will be opened and break the preheating circuit and the lamp will fire and operate normally with current flowing through the reactance, the relay coil and ballast lamp to the positive filament of the lamp.

In this starting operation the switch 14 only will open, while switch 16 remains closed, as shown in full lines in Fig. 3, and coil 10 will hold the switch 14 open as long as the lamp is in operation, but if the lamp is turned off coil 10 will be deenergized and switch 14 will immediately close, so that both switches 14 and 16 will be set for a restarting action. If, however, the relay coil does not pick up and open the relay contacts 15, 15', current will continue to flow through the main preheating circuit above described until the thermostatic switch heats up sufficiently to break its contacts 17, 17', as shown in dotted lines in Fig. 3, whereupon the preheating circuit will be broken and an inductive kick will be given due to the breaking of the circuit through the reactance to fire the lamp. As the switch 16 is normally closed and is rapidly opened by its snap action its time period of operation is reduced as compared with a normally open switch which must close and then reopen in a starting action, such as a glow switch type of starter. As when the lamp fires, the relay coil keeps the relay contacts 15, 15' open and keeps current off the heating coil of the thermostatic switch, the latter is always in a position to function in case the line circuit is opened and closed again.

Hence if the lamp is in operation and the line switch is opened to stop the lamp and then closed, with the thermostatic switch in normal position, all parts are ready

to commence restarting the lamp and this may fire, upon the application of line voltage and the preheating circuit, before the thermostatic switch has time to open its contacts, in which case relay contacts 15, 15' open the preheating circuit. This arrangement saves time in restarting a lamp which has been accidentally or inadvertently turned off. While the lamp is operating and coil 10 holds the relay contacts 15, 15' open, no current can pass through the heating coil 19 or contacts 17, 17' of the thermostatic switch, allowing the switch to cool in readiness for another operation.

The circuit organization shown in Fig. 4 is essentially the same as that shown in Fig. 1 except that the ballast lamp 9' is placed between the reactance and the joined portions of conductors 4 and 11 and resistance 18 is dispensed with. This circuit permits easy substitution of the combination relay and thermal switch starter for the present FS-44 starter with but little rewiring of existing fixtures. The lamp, however, will not fire on the application of line voltage alone, as it is practically short-circuited until the thermostatic switch opens and causes the reactance to give an inductive kick to start the lamp.

The circuit organization shown in Figs. 5 and 6 comprises the operating conductors 4a and 5a leading from the positive and negative line terminals to the electrodes. As shown, the conductor 4a here is connected with the short circuited positive filament 3 and has reactor 8a and ballast lamp 9a arranged therein between its line terminal point and the starter, while conductor 5a, which has the relay coil 10a arranged therein, is connected to the output terminal of the filament 2.

In this circuit arrangement the normally closed preheating conductor comprises branches 11a, 12a leading respectively from the conductor 4a to the starter and from the starter to the input terminal of the filament 2, the branches being connected by a relay switch 14a whose contacts 15a, 15a' are normally closed. Arc suppressing condenser 20' here is connected across the contacts 15a, 15a' of the switch 14a. The heater element 19a for the normally closed thermal switch 22 is connected between conductors 11a and 12a. On the negative side of filament 2 are arranged the contacts 22 of the thermal starter which normally short circuit the coil 10a of the relay. The relay switch members 14a and 16a are arranged to open their contacts 15a, 15a' and 17a, 17a' when current passes through the relay coil 10a.

Owing to the fact that the thermal switch contacts 22 and relay contacts 17a, 17a' shunt the coil 10a when starting, the relay cannot pick up when the line circuit is closed, so that preheating current flows through the ballast lamp, contacts of relay 15a, 15a', the heater element 19a, the cathode filament and through the contacts of the thermal switch 22 and contacts 17a, 17a' of the relay back to the negative side of the line. When the heater element has heated the thermal switch sufficiently, it opens its contacts 22, which cuts the coil of the relay into the circuit.

The relay then picks up and opens both sets of contacts, 15a, 15a', 17a, 17a'. The upper set 15a, 15a' thus breaks the circuit between the ballast lamp and filament to cause the lamp to fire, while the lower set 17a, 17a' breaks the circuit through the normally closed thermal switch contacts 22 so that when the heater element cools off and the thermal switch 22 recloses said switch contacts cannot short circuit the relay coil as long as the lamp is operating. Consequently the thermal switch will remain closed ready for another start when necessary, which can commence at once if the line circuit is opened and then immediately closed again to effect a substantially instantaneous restarting of the lamp.

In the circuit organization shown in Figs. 7 and 8 the construction in general is the same as that shown in Figs. 5 and 6 with the exception that the negative operating conductor is divided into two branches 5b, 5c connected at their distal ends respectively with the nega-

tive line terminal and with the output end of the cathode filament, the proximal ends of said branches being arranged to form switch circuit branches or connections 23 and 24, with which is associated a by-pass or shunt connection 25 connected at one end to the branch 5c and at its opposite or free end with the branch 5b through the relay coil 10b.

The heating resistance 19b is here arranged in the connection 23 and normally open thermal switch 22' is connected between the conductors 5c and 25. The relay here comprises switch members 14b and 16b. Switch member 16b is connected to conductor 12a and provided with a contact 17b normally engaging a contact 17b' on conductor 4a, while switch 14b has a contact end 15b normally engaging a contact 15b' on connection 23 to close this portion of the preheating circuit, and is movable therefrom, when attracted by the coil 10b, out of engagement with the contact 15b' and into engagement with a contact 15b² at the free end of the connection 25.

Normally, as relay switch 14b engages contact 15b' and connects the heating resistance 19b into circuit with the conductors 5b, 5c, and disconnects the coil 10b therefrom, no current can flow through the coil, but when the switch 14b moves into engagement with contact 15b² the heating resistance will be cut out of circuit with the conductors 5b, 5c and the relay coil 10b cut into circuit therewith. Thus the relay switch 14b has normally closed contacts and normally open contacts and is movable to break a normally closed preheating circuit through contacts 17b, 17b' and close a normally open or incomplete operating circuit. The relay coil is energized in parallel with the heating coil 19b of the thermal switch due to the closure of the normally open contacts 22' of the thermal switch and, when once energized, holds itself closed through the contacts 15b, 15b² and removes the heater-coil 19b of the thermostatic switch from the circuit.

With this arrangement the preheating circuit is broken by the relay contacts 17b, 17b' when the contacts 22' of the thermostatic switch close after a predetermined time to permit proper heating of the cathode filament. The arrangement shown in effect puts the heater element in the negative lead during starting and, once the lamp has fired, takes the heater element out of the circuit and puts the relay coil in the negative lead.

To more particularly set forth the operation of the circuit arrangement shown in Figs. 7 and 8, preheating current in starting flows through the reactor, ballast lamp, the relay switch contacts 17b, 17b', the cathode electrode relay switch contacts 15b, 15b' and the heater element of the thermostatic switch to the negative side of the line. A circuit is also established from the low side of the ballast lamp to the positive filament of the lamp to facilitate the starting action. When the preheating current has heated the thermostatic switch sufficiently, the switch closes its contacts 22', thus energizing the relay coil by placing the coil in parallel with the heater element, which causes the relay to disengage its contacts 15b, 15b' and engage its contacts 15b, 15b², whereby both sets of contacts are moved from the position shown in Fig. 7 to the position shown in Fig. 8.

Thus the upper set of relay contacts will break the preheating circuit to the cathode filament and cause the reactor to give an inductive kick to start the lamp, while the lower set of contacts will complete the operating circuit through the relay coil and establish a holding circuit keeping the thermostatic switch heater 19b deenergized while the lamp is operating. When the thermostatic switch cools contacts 22' reopen and are ready for another start.

In the arrangements shown in Figs. 1 to 4, inclusive, and 9 to 14, inclusive, two switches are employed, one of which is thermostatically operated and the other electro-magnetically operated to control the flow of preheating

and operating currents. These switches are preferably so constructed and arranged that they may be compactly combined and enclosed in a plug-in "can" or casing 26 (indicated by dotted lines) of conventional type. In practice the circuit arrangements of Figs. 1 and 4 may be employed with very little rewiring from a circuit arrangement designed to use a conventional starter, while the arrangement of Figs. 5 and 7 may be used without any rewiring.

Both the arrangements shown in Figs. 5 and 7 are reversible in the same socket employed for an FS-44 starter and have the same advantage of Figs. 1 and 4 of using full lamp current to energize the relay coil to hold the relay switch in lamp operating position once the lamp has fired.

It is to be understood that in the circuit organizations shown in Figs. 1, 4, 5 and 7 the positive filament may be short-circuited or left open-circuited, depending upon the characteristics of the particular lamp to be used in the circuits.

In Figures 9 to 14, inclusive, I have exemplificatively shown a type of unitary starter embodying a thermostatic starter switch and a relay which may be mounted in a can or casing having contact prongs for engagement with the switch socket of a fluorescent lamp circuit. The construction shown is one adapted for use in connection, for example, with the circuit arrangements shown in Figs. 1 and 4, but with little or no wiring or structural changes may be used in connection with the circuit arrangements illustrated in Figs. 5 to 8, inclusive. This starter comprises a can or casing A having a normally open lower end adapted to be closed by an insulating head or disk B carrying plug-in prongs C, D, E, and F to engage the socket terminals.

Supported by the disk B is a spool-shaped coil form G about which is wound the coil 10, the terminals of which are respectively connected by the leads 4 to the prongs D and E. A magnetic core H extends upwardly from below into the coil form and is fixed at its lower end to the coil form and has its upper end terminating adjacent to the top of the form and supported therein by an insulating block h fixed to the form. Arranged alongside the coil is the switch member 14 carrying at its upper end the contact 15 and having at its lower end a terminal i suitably fixed to the coil form and insulated at such point from the core H. Terminal i of the switch 14 is connected by the lead 11 to the prong C on the starter casing head B. Extending upward through the form is a conductor j having a lower terminal j' and an angularly bent upper part provided with a U-bend j² and a depending free end, the latter carrying the fixed contact terminal 15' for coaction with contact 15 of switch 14.

An adjusting screw or bolt j engaging the bend j² provides for adjustment of contact 15' relative to contact 15. Contact 15' is connected through conductor j, terminal j', and the input branch of conductor 13 with a terminal 13a connected at one end with the heater coil 19, which is connected at its opposite end to a terminal 13b connected in turn to a member k carrying the fixed contact 17' coacting with the contact 17 of the thermostatic switch 16. The parts 13, 19, 13b, k and 16 are mounted on an insulated disk L supported from the head B by a terminal m conductively connecting the switch member 16 with the prong F. The disk L is formed with a hollow boss n which houses the concaved disk 16', the resistance 19 and the stem connecting said disk 16' with the switch member 16 and whereby said switch member can move to open position to break the preheating circuit therethrough when the disk 16' is heated.

Switch member 16 is so constructed that it tends to move to the open position of contacts 17, 17' but is prevented from doing so by the stem connected to said disk 16', until disk 16' is sufficiently heated to reverse its curvature. Condenser 20, as shown, is connected to prongs C and F and hence across conductors 11 and 12. The arrangement of parts 14, 15, 15' is reverse to that

shown in Figs. 1 and 4, but said parts operate in the same way. The operation of this unitary starter will be readily understood by reference to the description of the operation of the circuit arrangement shown in Figs. 1, 2, 3 and 4. This starter, as stated, will operate in connection with the circuit arrangement shown in Figs. 1 and 4 without changes and may be adapted to operate with the other circuit arrangements by slight changes in wiring or construction of parts.

It is to be understood that while, for convenience in use, both switches and their connections are preferably placed in a starter can, which gives practical advantages, these parts, within the scope of my invention, may be placed partly within and partly without the can. It is also to be understood that while the circuit organizations are shown for example as being designed for use in connection with D. C. lamps, they may with little or no changes or suitable changes be used in connection with A. C. lamps.

It will also be understood that other changes may be made without departing from the invention, the scope of which is set forth in the appended claims.

Having thus described my invention, I claim:

1. A system for supplying preheating and operating current to a discharge device comprising the combination of a supply circuit, a gaseous electric discharge device having two electrodes, at least one of which is constructed to receive preheating current, a relay having an operating winding and normally closed contacts, means including an inductive reactance device and said winding for connecting said electrodes with said supply circuit so that said winding is energized by the operating current of the discharge device after the device fires, a thermally operated switch having a heater and normally closed contacts, and a preheating circuit capable of producing firing temperature electrode heating, said circuit including in series connection said relay contacts and said thermal switch contacts and heater and the electrode to be preheated, said preheating circuit being connected across the discharge device and said winding in series connection so that the opening of said thermal switch causes said discharge device to fire by an inductive voltage kick and so that the opening of said relay contacts by the resulting establishment of the operating current through the discharge device prevents the re-establishment of the preheating circuit when said thermal switch cools and recloses.

2. A system for supplying preheating and operating current to a discharge device comprising the combination of a supply circuit, a gaseous electric discharge device having two electrodes, at least one of which is constructed to receive preheating current, a relay having an operating winding and normally closed contacts, means including an inductive reactance device, a ballast and said winding for connecting said electrodes with said supply circuit so that

said winding is energized by the operating current of the discharge device after the device fires, a thermally operated switch having a heater and normally closed contacts, and a preheating circuit capable of producing firing temperature electrode heating, said circuit including in series connection said relay contacts and said thermal switch contacts and heater and a current limiting resistance and the electrode to be preheated, said preheating circuit being connected across said discharge device and said ballast 10 and said winding in series connection so that the opening of said thermal switch causes the discharge device to fire by an inductive voltage kick and so that the opening of said relay contacts by the resulting establishment of the operating current through the discharge device prevents the re-establishment of the preheating circuit when said thermal switch cools and recloses.

3. A system for supplying preheating and operating current to a discharge device comprising the combination of a supply circuit, a gaseous electric discharge device 20 having two electrodes, one of which is constructed to receive pre-heating current, a relay having an operating winding and normally closed contacts, means including an inductive reactance device, a ballast and said winding for connecting the other electrode of said device with said supply circuit so that said winding is energized by the operating current of the discharge device after the device fires, a thermally operated switch having a heater and normally closed contacts, and a preheating circuit capable of producing firing temperature electrode heating, said circuit including in series connection said relay contacts and said thermal switch contacts and heater, one end of said circuit being connected to said ballast and the other end of said circuit being connected to one end of the electrode to be preheated, the opposite end thereof being 30 connected to the opposite side of said supply circuit, said series connected relay and switch contacts being thereby connected across said electrodes and said winding in series connection so that the opening of said thermal switch causes the discharge device to fire by an inductive voltage 35 kick and so that the opening of said relay contacts by the resulting establishment of the operating current through the discharge device prevents the re-establishment of the preheating circuit when said thermal switch cools and recloses.
